UNITED STATES PATENT OFFICE.

DAVID R. FITZ SIMONS, OF BEAVER, PENNSYLVANIA.

STONE-PICKING MACHINE.

1,263,658.

Specification of Letters Patent. Patented Apr. 23, 1918.

Application filed August 17, 1917. Serial No. 186,772.

To all whom it may concern:

Be it known that I, DAVID R. FITZ SIMONS, a citizen of the United States, residing at Beaver, in the county of Beaver and State 5 of Pennsylvania, have invented certain new and useful Improvements in Stone-Picking Machines, of which the following is a specification.

This invention relates to stone gatherers 10 and has for its principal object the production of a machine so constructed as to gather stones in the path of its movement.

Another object of this invention is the 15 production of a stone gatherer which includes an efficient means for supporting a scoop on the top of the front axle and a box upon the lower portion of said axle, thus permitting a conveyer to be secured to the box, thus causing the forward end of the 20 conveyer to be below the rear end of the scoop to allow the stones gathered by the scoop to be deposited upon the conveyer.

A still further object of this invention is the production of a stone gatherer wherein 25 the scoop is hingedly supported thereby allowing stones and soil to be deposited upon a conveyer when the machine is in use, although when it is not desired to gather stones or when the machine is being moved 30 from place to place the forward portion of the scoop may be lifted to an elevated position.

Other objects and advantages will be apparent during the course of the following 35 description.

In the accompanying drawings forming a part of the description and wherein like numerals are employed to designate like parts throughout the same,

40 Figure 1 is a top plan view of the stone gatherer showing the same when in condition to be used.

Fig. 2 is a central longitudinal view 45 through the stone gatherer.

Fig. 3 is an enlarged fragmental sectional view through a portion of the device, illustrating specifically the mounting of the conveyer frame on the rear axle, and the means 50 for shifting the clutch.

Fig. 4 is an enlarged fragmental sectional view through the forward portion of the machine, showing clearly the connection between the scoop and forward axle.

Fig. 5 is a fragmental transverse sec- 55 tional view through the rear portion of the

machine illustrating the manner in which power is imparted from the driving wheels to the conveyor.

Fig. 6 is a fragmental plan view of a portion of the scoop.

Fig. 7 is an elongated sectional view 60 through the portion of the scoop showing specifically the locking connection for the two sections of the scoop.

Fig. 8 is a sectional view through a portion of the conveyer showing the manner 65 in which the same is mounted upon its track.

Fig. 9 is another sectional view of the 70 conveyer illustrating the manner in which the bars of the conveyer are secured to the chains thereof.

Referring to the accompanying drawings by numerals, it will be seen that the stone gatherer comprises a forward axle 1 having 75 supporting wheels 2, while the yoke 3 is secured to the forward axle 1 and has the usual pole 4 and whiffletree 5 secured thereto. Thus it will be seen that means are provided for propelling the forward 80 axle 1.

The scoop comprises a primary section 6 and the auxiliary section 7 which are hingedly secured together as shown at 8. These sections 6 and 7 have flanges 9 formed 85 thereon which will direct the earth and stones upwardly as the machine digs into the ground as illustrated in Fig. 2. In order to hold the scoop in an operative position the sections 6 and 7 have alined de- 90 pressed grooves 10 in which the bars 11 are reciprocally mounted. By referring particularly to Figs. 6 and 7, it will be seen that the bars 11 are shifted to the forward 95 ends of the grooves when the scoop is in an operative position thereby holding the scoop against collapsing. By referring particularly to Fig. 6 it will be seen that the grooves and bars are of a dove-tailed construction as shown in dotted lines, whereby 100 the bars will be held against accidental displacement. Front axle 1 has lugs 12 projecting therefrom through which suitable securing means may be passed for fixedly mounting the primary section of the scoop 105 upon this forward axle. This scoop terminates at a point above the forward axle so that as the stones and soil are urged upwardly by the passing of fresh stones and soil on to the lower end of the scoop, the 110

110

stones and soil will finally fall from the inner end of the scoop as shown in Fig. 4. If it be desired to move the machine from place to place or when it is not desired to 5 gather stones, the bars 11 may slide toward the upper end edge of the grooves 10 thereby releasing the auxiliary section 7 of the scoop permitting this auxiliary section to be swung upwardly to be secured in an inoperative 10 position.

An elongated rectangular box 13 is secured by the king bolt 14 of the front axle 1 as shown in Fig. 4 and this box 13 depends below the front axle 1. This box is further 15 provided with a semi-circular flange 15 extending longitudinally thereof and transversely of the machine and this semi-circular flange 15 constitutes a guide as will be hereinafter shown.

20 The rear axle 16 is provided with supporting wheels, which wheels comprise hubs 17, spokes 18 and broad treads 19. A bracket 20 is carried adjacent each end of the rear axle 16 and is formed upon this axle so as 25 to be held against accidental movement. These brackets 20 are provided with sleeves 21 as shown in Fig. 2 and with forwardly projecting portions 22. The auxiliary drive shaft 23 is carried by the sleeves 21 and 30 extends transversely of the machine and has sprockets 24 adjacent its ends as shown in Fig. 5. These sprockets 24 are also provided with integral pinions 25 for purposes to be set forth. It should be further understood 35 that plates 26 are spaced from the spokes 18 of the rear wheels by the spacers 27 although these plates 26 are fixed to rotate with the rear wheels by the bolts or other securing members 28. These plates 26 are 40 provided with teeth 29 projecting inwardly therefrom as also shown in Fig. 5. A loose sleeve 30 is positioned upon the rear axle 16 adjacent each end thereof and this loose sleeve 30 has a hub 31 keyed thereon and 45 this hub 31 has teeth 32 adjacent its periphery. A gear 33 is also keyed upon each hub 30, whereby rotary motion may be imparted to the gears 33.

The side rails 34 of the conveyer are 50 provided with a transverse supporting bar 35 which is carried upon the forwardly extending portion 22 of the brackets 20 whereby these side rails will be supported adjacent their rear ends. The forward ends of these 55 side rails 34 extend to a point adjacent the box 13 as shown in Fig. 2. The lower supporting tracks 36 are fixed in any suitable manner upon the side rails 34 and project longitudinally of these rails, although adjacent the forward ends of these side rails 34 the supporting tracks 36 pass through the box 13 and are supported by this box as 60 shown in Fig. 4. In this manner it will be seen that the conveyer is connected to the 65 forward and rear axles of the machine.

Pinions 37 are rotatably mounted upon the forward ends of the tracks 36 in front of the box 13 and adjacent the guide flange 15.

The conveyer has side chains 38 which pass around the sprockets 24 upon the supporting shaft 23 adjacent the rear end of the conveyer and also around the sprockets 37 adjacent the box 13 at the forward end of the conveyer. These chains 38 have parallel bars 39 secured thereto as shown at 40 in 70 Fig. 9. These chains rest upon the supporting tracks 36 as illustrated in Figs. 8 and 9 whereby the bars will be supported throughout their entire journey when rocks are carried thereon. It should further be 80 understood that guide flanges 41 may also be carried by the side rails 34 and these flanges 41 are adapted to overhang the chains of the conveyer so as to protect these chains from injury and at the same time 85 prevent dirt from clogging these chains.

The castings 42 are supported upon the supporting shaft 23 or in any other suitable manner and project rearwardly for a short distance beyond this shaft. The supporting 90 rods 43 project upwardly from the castings 42 and are provided with a portion 44 from which project the lugs 45. Pivot bolts 46 are supported by the lugs 45 and carry the levers 47. Links 48 project from the levers 95 47 and are connected to the yokes 49 mounted in the grooves 50 of the hubs 31. Thus it will be seen that as the levers 47 are shifted inwardly at their upper ends they will cause the links 48 to move the yokes 49 outwardly, thus moving the teeth of the hub 31 into engagement with the teeth 29 of the plates 26. This action will cause the sleeves 30 to be shifted so as to move the gears 33 into meshing engagement with the pinions 100 25. At this time the rear wheels will be rotating and as a consequence rotary motion will be imparted to the chains 38 thus causing the bars 39 to be moved upwardly upon the tracks of the side rails of the conveyer. 105

110 It is of course obvious that as soon as it is desired to stop the movement of the chains and bars, the levers 47 may be swung outwardly thus drawing upon the links 38 thus causing to draw the yoke 49 for moving the teeth 32 from engagement with the teeth 29.

115 It should be noted that as the chains and bars are in operation, they will be prevented from hanging upon the forward portions of the 120 elongated box by the provision of the guide flange 15 while the chains are provided with sufficient slack to enable the chains and bars to pass safely around under the rear axle as shown in Figs. 2 and 3.

125 When the stone gatherer is in operation the auxiliary section of the scoop is swung to an operative position and held by the bars 11 so as to assume the position shown in Figs. 1 and 2. At this time the operator 130

should shift the levers 47 inwardly thus causing the hubs to mesh with the teeth, plates 26 thereby imparting movement to the chains and bars of the conveyer. As the 5 stone gatherer is driven forwardly by drive animals secured to the whiffle trees or by any other suitable motor power applied to the gatherer, it is obvious that stones and earth will be dug up by the forward portions 10 of the scoop. As fresh earth is gathered on to a lower portion of the scoop, the earth and stones will be pushed over the inner end of the primary section of the scoop to fall onto the bars of the conveyer. 15 From the foregoing description, it will be seen that a very efficient stone gatherer has been provided, which will efficiently gather stones and earth. It should further be noted that very efficient supporting means 20 are provided for the chains which will prevent the chains from clogging or becoming inoperative in operation and at the same time will guide the chains for the operation thereof. It should also be noted that efficient means are provided for supporting the side rails of the conveyer, and the supporting shaft upon the rear axle. It is of course 25 obvious that many minor detailed changes may be made in the construction of this invention and it is not intended to limit the construction of this invention to the specific form herein shown but it is intended to include all such forms of the invention within 30 the scope of the claims. 35 What I claim is:

1. In a stone gatherer, the combination of an axle having a king bolt, means for supporting said axle, a scoop secured on the top of

said axle, a box supported by said king bolt and a conveyer secured to said box whereby 40 stones and earth gathered by said machine may be deposited upon said conveyer and said box holding said conveyer against displacement.

2. In a stone gatherer, the combination of 45 a forward axle, means for supporting said axle, gathering means carried by the top portion of said axle, a bolt projecting through said axle, an elongated box pivotally mounted upon said bolt, a conveyer secured 50 within said box, means for driving said conveyer, whereby stones and earth gathered by said gathering means may be deposited upon said conveyer.

3. In a stone gatherer, the combination of 55 a supporting axle, means for supporting said axle, a gathering means carried by the top portion of said axle, an elongated box secured upon the lower portions of said axle, and a conveyer means secured to said box. 60

4. In a stone gatherer, the combination of a supporting axle, means for supporting said axle, a gathering means carried by the top portion of said axle, an elongated box pivotally mounted upon said axle in a plane 65 below said gathering means, and a conveyer means connected to said box, and said box being adapted to accommodate movement of said axle with respect to said conveyer 70 means.

In testimony whereof I affix my signature in presence of two witnesses.

DAVID R. FITZ SIMONS.
